CLAIM

The ornamental design for a container for blood samples or the like, as shown.

DESCRIPTION

FIG. 1 is a top perspective view of a container for blood samples or the like showing my new design;

FIG. 2 is a bottom perspective view thereof;

FIG. 3 is a top perspective view showing a modified form of my new design wherein only the relative proportions have been changed;

FIG. 4 is a bottom perspective thereof; and,

FIG. 5 is an elevational view of the container of FIG. 1.

FIG.1

FIG.2

FIG.3
